(No Model.)

A. D. TYRILL.

CLOCK CASE.

No. 399,097.

Patented Mar. 5, 1889.

UNITED STATES PATENT OFFICE.

ALFRED D. TYRRILL, OF NEW HAVEN, CONNECTICUT, ASSIGNOR TO THE NEW HAVEN CLOCK COMPANY, OF SAME PLACE.

CLOCK-CASE.

SPECIFICATION forming part of Letters Patent No. 399,097, dated March 5, 1889.

Application filed November 5, 1888. Serial No. 289,991. (No model.)

To all whom it may concern:

Be it known that I, ALFRED D. TYRRILL, of New Haven, in the county of New Haven and State of Connecticut, have invented a new 5 Improvement in Clocks; and I do hereby declare the following, when taken in connection with accompanying drawings and the letters of reference marked thereon, to be a full, clear, and exact description of the same, and which 10 said drawings constitute part of this specification, and represent, in—

Figure 1, a front view of the clock complete; Fig. 2, a side view of the same; Fig. 3, a rear view of the connection, the back turned to 15 the open position to show the movement; Fig. 4, an inside view of the flange looking toward the front; Fig. 5, a view of the front portion of the case looking from the rear, the movement removed; Fig. 6, a front view of 20 the movement with the dial attached and as removed from the case; Fig. 7, a side view of the same; Fig. 8, a horizontal section showing the movement as locked in the case.

This invention relates to an improvement in 25 that class of clocks in which the movement is of circular shape and arranged within a sheet-metal case of corresponding circular shape. In the more general construction of this class 30 of clocks the movement is secured in the case by screws through the back or sides, and the winding and setting device projects through the back of the case, and generally the dial is applied after the movement is introduced 35 into the clock, and is secured independent of the movement, so that before the movement can be removed from the case it is generally necessary to detach the dial and pointers.

The object of my invention is to so construct the movement and attach it to the case 40 that the movement as a whole, including the dial and pointers, may be removed or introduced without detachment of any of the parts, and also so that the pointing and setting devices may be entirely within the case; and 45 the invention consists in a case composed of two parts, the division being in a plane at right angles to the axis of the case, the one part constituting the front and the other the back portions of the case, combined with the 50 movement having its front plate constructed or provided with a flange of substantially the

internal diameter of the case, and to which flange or plate the dial is secured, the said flange constructed with notches upon its edge and a cam-shaped surface running from said 55 notches, the interior of the case provided with studs over which the said notches in the flange may pass as the movement is inserted from the rear of the case, and so that when so inserted the movement with the said flange may 60 be rotated to bring the said cam-shaped surfaces against the said studs, and thereby removably interlock the movement with the case, as more fully hereinafter described.

The case is composed of two parts, A representing the front part, and B the rear part, the parts of circular shape, and the division is in a plane at right angles to the axis, the two parts hinged together, as at a, and preferably the shape of the two parts gives to the 70 case a watch-like appearance. For convenience the case is provided with a ring, C, by which the case may be hung or handled as a watch is hung or handled. The two parts are made from sheet metal struck to the required 75 shape, and so that the back may be closed upon the front or opened like the back of a watch.

The movement is composed of a front plate, D, and rear plate, E, connected by posts, (see 80 Figs. 7 and 8,) the mechanism being arranged between and on the plates in the usual manner, there being no novelty in the movement itself so far as this present invention is concerned. Upon the front plate of the movement a flange, F, is formed or attached, (here represented as attached.) This flange corresponds in diameter to the internal diameter 85 of the front portion, A, of the case. The edge of the flange is turned rearward, so that its 90 outer surface, b, is parallel with and so as to rest against the inner surface of the case, as seen in Fig. 8.

The dial-plate G is best secured to the flange F by means of tongues d, cut from the flange, 95 as seen in Figs. 6 and 7, and which are closed down over the outer edge of the dial-plate G, as also seen in Figs. 6 and 7. The flange is best made separate from the plate D and secured thereto; but in any case it becomes substantially a part of the front plate.

Through the edge of the flange F, at one or

more points, notches *e* are formed, (see Figs. 3 and 4,) the notches being represented as diametrically opposite each other, and from the notches the edge of the flange inclines, as seen in Fig. 7, so that the said edge is oblique to the plane of movement, the incline of the edge being rearward from the respective notches. Upon the inside of the front portion of the case internally-projecting studs 10 *f* are formed in the same relative position to each other as the notches *e* in the flange *F* of the movement, and so that the movement may be set into the case, the notches *e* permitting the movement to reach its place of rest in the 15 case and against the border *H* inside the glass *I*, as seen in Fig. 8. This brings the inclined edge of the flange at the notches below the studs *F*, and then a partial rotation of the movement will correspondingly turn the 20 flange under the studs *f* until a firm bearing is attained, as indicated in Fig. 8, so that the studs bearing upon the flange serve to hold the movement firmly in the case, and the position at which this bearing is reached should 25 be such that the figures on the dial will be in their proper relative position to the supports for the case.

When it is desired to take the movement from the case, a return rotation imparted to 30 the movement will bring the notches *e* into line with the studs *f* in the case. Then the movement may be readily taken from the case, no other means of securing being necessary than that which is afforded by the said 35 flange and the studs in the case. The hinged back is given a shape which will cover the winding and setting devices, and is preferably made of a convex shape, as shown, and so that it may close upon the case and retain 40 its closed position, substantially as the back of a watch-case is closed.

To wind the clock or set the pointers, it is only necessary to open the back, and easy access is had to the pointing or setting devices. 45

The shape of the exterior of the case may be varied to suit the tastes or requirements of the trade, such shape constituting no part of the present invention.

I have represented the two parts of the case as hinged together, and this I prefer as a matter of convenience; but it will be understood that they may be removably set together in any convenient or known manner without de- 55 parting from the spirit of this invention.

In case the parts are hinged together, as shown, it will usually be necessary to cut a notch, *g*, in the flange, as seen in Figs. 3, 4, and 5, to permit the flange to escape the hinge when the movement is introduced or removed. 60

I do not wish to be understood as claiming, broadly, a time-movement constructed so as to be removably secured in its case by a bayonet or interlocking joint. 65

I claim—

1. A clock-case made in two parts, the division being in a plane at right angles to the axis of the case, one of the parts of the case constructed with radially-projecting studs *f* upon its inside, combined with a movement 70 having its front plate provided with a flange corresponding to the shape of the interior of the case, the edge of the flange adapted to rest against the inner surface of the case, the said flange constructed with notches *e*, corresponding in position to the studs *f* of the case, and the edge of the flange from the recesses inclined to the plane of movement, substantially as described, and whereby the said notches permit the flange of the movement to 75 pass into the case beyond the studs, and then by a partial rotation of the movement to bring the inclined edges of the flange under said studs. 80

2. A circular clock-case made from sheet 85 metal in two parts, the division being in a plane at right angles to the axis of the case, the one part, *A*, being the front and the other part, *B*, the rear part, the front part provided with a glass, *I*, and a border, *H*, resting upon 90 the inside of the glass, combined with a movement constructed with a circular flange, *F*, corresponding in shape to and so as to rest against the interior of the front portion of the case, the said flange constructed with two or 95 more notches, *e*, through its edge, and the edge of the case from the notches inclined to the plane of movement, the said front portion of the case provided with studs *f*, corresponding to the notches *e* in the flange of the movement, and whereby the said movement and its flange are removably secured in the case, and also serve to secure the glass and its holding in place, substantially as and for 100 the purpose described.

ALFRED D. TYRRILL.
